UNITED STATES PATENT OFFICE.

WILLIAM A. JAMESON, OF NIAGARA FALLS, NEW YORK.

DESIGN FOR A CANDLE-HOLDER.

No. 39,645.

Specification for Design.

Patented Oct. 27, 1908.

Application filed February 21, 1908. Serial No. 417,179. Term of patent 7 years.

To all whom it may concern:

Be it known that I, WILLIAM A. JAMESON, a citizen of the United States, residing at Niagara Falls, in the county of Niagara and State of New York, have invented a new, original, and ornamental Design for Candle-Holders, of which the following is a specification, reference being had to the accompanying drawing, forming a part thereof.

This invention relates to the design of candle holders and the like. Its object is to devise ornamental and harmonious features of design in connection with devices of the above general nature.

Referring to the accompanying drawing, which is a front view of an illustrative embodiment of the several features of this invention, there is shown a supporting figure 1 bearing a horn 2, upon which rests a ring or ball 3, provided with a short supporting column 3^a. Mounted upon the latter member is a candle socket 4, and extending laterally

from the wall 3 are arms 5, here shown as four in number, each of which supports a socket 4, through a suitable connection 6.

A characteristic feature running through the entire holder here shown is its representation of parts of a pond lily, a leaf being shown at 7, the arms 5 being of the form of the stems of the above flower, and the sockets representing the blossoms thereof.

It may be noted that various features of design of the holder illustrated in the drawing are of independent value, although peculiarly adapted to harmonize with and form a unitary design with other features here shown.

I claim:

The ornamental design for the candle holder, as shown and described.

WILLIAM A. JAMESON.
